RAIL JOINT

John T. Baldwin, Chattanooga, Tenn.

Application November 1, 1937, Serial No. 172,271

1 Claim. (Cl. 238—242)

My invention relates to rail joints and more particularly to rail joints of the expandible type.

One of the principal objects of my invention is to provide a rail wherein the rail sections 5 are capable of expansion and contraction and at the same time prevented from lateral as well as vertical dislodgement relative to each other.

Another object of my invention is to provide a rail joint of the above described character 10 formed in a manner to effect a positive locking of the rail sections together and which is capable of ready assembly and disassembly of the sections.

Other objects and advantages will be apparent 15 from the following description, appended claim and annexed drawings.

Referring to the drawings wherein like reference characters designate like parts throughout the several views:

20 Fig. 1 is a perspective view of my invention.

Figs. 2 and 3 are perspective views of the interlocking rail end sections in disassembled position.

Fig. 4 is a top plan view of my invention.

25 Fig. 5 is a horizontal section.

Fig. 6 is a transverse section taken on the line 6—6 of Figure 4.

Fig. 7 is a top plan view illustrating one of the initial positions in disassembling the sections.

30 Fig. 8 is a top plan view illustrating another step in disassembling the sections.

Fig. 9 is a sectional view taken on the line 9—9 of Figure 7.

35 Fig. 10 is a sectional view taken on the line 10—10 of Figure 8.

Fig. 11 is a transverse section illustrating one of the final steps in disassembling the sections.

Fig. 12 is a similar view to Figure 11 illustrating the final step in disassembling the sections and the initial step in assembling the sections.

Fig. 13 is a fragmentary elevation of the rail chair.

45 Fig. 14 is a fragmentary bottom plan view of the rail chair.

In practicing my invention I provide, as illustrated in the drawings, connected rail end sections A and B of rails and which are fashioned 50 in a manner to form my novel joint hereinafter described. Inasmuch as the sections A and B are of a substantially identical construction, whereby the same are adapted for interlocking engagement with each other, a detailed description of section A will suffice, it being under-

stood, for the purpose of description, that the reference numerals indicative of parts of section A are set forth with the exponents "a" as indicative of like parts of section B.

Section A is fashioned with the usual head 5, flange 6 and web 7. The web is formed with an enlarged portion 8 extending longitudinally beyond the outer end of said section for engagement with section B and terminates in a vertically extending outer end face 9.

The head 5, at a point substantially intermediate of the inner end of the portion 8 and outer end of the section A, is segmented to form an inner vertical wall extending through said head and having a right angularly disposed shoulder 10 located substantially intermediate of the length of said wall forming parallel extending walls 11 and 12 respectively. The wall 11 terminates rearwardly in a transverse wall 13 effecting jointure with a vertically extending and outwardly inclined wall 14 forming a cuneiform section 15 on the head 5. The outer end of the head 5 adjacent the portion 8 is fashioned with a vertical and inwardly extending wall forming a cuneiform section 16 on the end 20 of said head. The flange 6 between the wall 13 and shoulder 10 is segmented to form rear and front flange sections 17 and 18 respectively. The lateral face of the web 7 oppositely disposed from the face formed with the 25 portion 8, and between the wall 13, shoulder 10, flange sections 17 and 18, is formed with a vertical and longitudinally extending wall 19. The upper end of said wall 19 is fashioned with a right angularly disposed face aligned with the 30 under faces of the cuneiform sections 15 and 16 and thereby forms a shoulder 20 right angularly disposed in relation to the vertical face of the wall 11. The outer end of the wall 19, subjacent the wall 12, is fashioned with a slot 40 for permitting the section 15a to be inserted therethrough for locking engagement with section 16. The upwardly and outwardly extending face of the wall 19 forms front and rear upwardly extending transverse shoulders 21 and 45 22 respectively.

The web 7 and enlarged portion 8 are formed with transverse apertures 23 for the reception of suitable bolts 24 for clamping the sections A and B together. The apertures 23 are elongated on one section in a manner to register with cylindrical apertures in the opposite section whereby to permit contraction or expansion of the sections relative to each other and the enlarged portions 8 are countersunk about 50 55

the cylindrical shaped apertures and receive the heads of the bolts secured therethrough to prevent relative movement between the bolts and nuts.

5 The sections A and B, being in the disassembled position shown in Figure 2, are assembled in the following manner: the section A is canted slightly below the section B to position the wall 12 against the wall 19a below the shoulder 29a 10 and the front flange section 18 between the front and rear flange sections 18a and 17a respectively, as clearly illustrated in Figure 12. From this position, section A is moved upwardly positioning the walls 11 and 12 adjacent the 15 faces 12a and 11a respectively, the shoulders 10 and 10a in abutting engagement, the cuneiform section 16 passing between the cuneiform section 15a and wall 11a and over the shoulder 29a, and the cuneiform section 15 passing between the cuneiform section 16a and the web portion 8a as illustrated in Figure 11.

From the last described position, the flange end of the section A is moved inwardly to assume a parallel horizontal position with the 25 flange end of section B as illustrated in Figure 10. From this position, the sections are moved transversely whereby the faces 11 and 12 abut the faces 12a and 11a respectively, as illustrated in Figures 7 and 9, and in which the shoulders 30 10 and 10a are in abutting engagement.

From this last described position, the sections A and B are moved longitudinally relative to each other to effect a spacing between the shoulders 10 and 10a, wall 13 and end of cuneiform 35 section 16a, and end of cuneiform section 16 and wall 13a. In this position the bolts 24 are passed through the apertures 23 and nuts 25 threaded on said bolts to bind the parts together.

From the foregoing it will be apparent that 40 by spacing the cuneiform sections apart thereby moving the shoulders 10 and 10a, (as illustrated in Figure 4) contraction or expansion of the sections is compensated for. It is to be noted that the enlarged portions 8 and 8a of the respective webs extend beyond the outer 45 ends of the sections and seat between the head and flange of the adjacent section, thereby reinforcing the structure.

Obviously, while the joint permits relative longitudinal movement of the rail sections for the 50

purpose of contraction or expansion, lateral or vertical movement between the sections is prevented due to the interlocking of the flange sections, horizontally extending shoulders, cuneiform sections and the extending portions 8 5 and 8a.

For the purpose of securing the rails to the usual cross ties, I employ a rail chair having coacting sections 30 and 31 extending longitudinally of the rail sections A and B and formed 10 with upwardly extending arms 32 and 33 formed with channels to embrace the flanges 6 and 6a of the rails as clearly illustrated in Figure 6. Subjacent the bottom and intermediate of the length thereof, the sections 30 and 31 are formed 15 with recessed lugs through which is secured a bolt and nut 34 for clamping the sections together about the flanges 6 and 6a. Adjacent the outer ends, the chair sections 30 and 31 are formed with slots 35 for receiving the shanks 20 of rail spikes whereby the chair is secured to the cross ties.

What I claim is:

A rail joint of the class described, comprising, 25 a pair of identical abutting rail sections formed with head, web and flange sections respectively, each of said head sections fashioned with an inner and outer cuneiform section, said inner cuneiform section spaced inwardly from the rail end face, each of said cuneiform sections having a vertical longitudinally inclined abutting surface, said abutting surfaces being parallel, said outer cuneiform section terminating in an end face flush with the rail end face and the inner and outer cuneiform sections of one rail 30 section laterally engaging the outer and inner cuneiform sections respectively of the abutting rail section, each of said web sections being partially cut away and fashioned with a horizontal shoulder abutting the lower face of the 40 cuneiform section of the abutting rail section, each of said flange sections being cut away adjacent the end thereof to accommodate the end of the flange section of the abutting rail section, said cuneiform sections coacting with each 45 other, said shoulders and said cut away flange sections to prevent relative vertical movement and permit longitudinal movement of said rail sections relative to each other.

JOHN T. BALDWIN. 50
